UNITED STATES PATENT OFFICE.

RUDOLF LIBENSCHEK, OF PITTSBURGH, PENNSYLVANIA, ASSIGNOR OF ONE-THIRD
TO SLAVK LOVRENCIC, OF BELLEVUE, PENNSYLVANIA, AND ONE-THIRD TO PAUL
RADOCAJ, OF PITTSBURGH, PENNSYLVANIA.

MUFFLER.

1,395,920.

Specification of Letters Patent.

Patented Nov. 1, 1921.

Application filed February 6, 1920. Serial No. 356,589.

To all whom it may concern:

Be it known that I, RUDOLF LIBENSCHEK, a citizen of the Republic of Jugo-Slavia, residing at Pittsburgh, in the county of Allegheny and State of Pennsylvania, have invented new and useful Improvements in Mufflers, of which the following is a specification.

This invention relates to mufflers, and 10 more particularly to a muffler specially adapted for use in connection with automobile internal combustion engines, and for similar purposes.

One of the main objects of the invention 15 is to provide a muffler of the character stated which may be readily produced at small cost and quickly and easily applied. Another object is to provide a muffler which will permit ready escape of the exhaust gases so as to 20 eliminate back pressure in the exhaust manifold of the engine. Further objects will appear from the detailed description.

In the drawings:—

Figure 1 is a central sectional view taken 25 through a muffler constructed in accordance with my invention approximately in the plane of section line 1—1 of Fig. 2.

Fig. 2 is a transverse section through the muffler taken substantially on line 2—2 of 30 Fig. 1.

Fig. 3 is a fragmentary side view of the inner end portion of the central member of the muffler.

Fig. 4 is an end view of the same.

The muffler is cast as a unit and includes 35 a central tube 1 for receiving the exhaust gases, the inner portion of this tube being slightly flared and split to form a clamping element 1^a adapted to receive and be secured 40 about exhaust pipe 2 of an internal combustion engine. Tube 1 communicates at its outer end with an elbow 3^a which connects the outer ends of the inner arms of two exhaust discharge tubes 3 of elongated U- 45 shape, the outer end of the outer arm of each of these tubes being flared as at 3^b to facilitate discharge of the exhaust gases. Each of the discharge tubes 3 is provided in each arm with a plurality of baffles 4 50 which are disposed in staggered relation and inclined oppositely to the direction of flow of the exhaust gases. Tube 1 is provided with similar baffles 5, the outermost baffle 5^a of which is disposed at right angles to

the other baffles 5. An inwardly tapering 55 dividing element 6 extends inwardly from the central portion of elbow 3^a and serves to divide the column of exhaust gases discharged from baffle 5^a into two substantially equal portions which flow through the respective discharge tubes 3.

I have found by experience that very good results can be obtained with a muffler constructed in this manner, even when the baffles 4 and 5 are omitted. When the 65 baffles are employed there is practically no sound produced and, for this reason, I prefer to employ the baffles, although there is very little sound produced when the baffles are omitted. As the exhaust gases can flow 70 freely through the tube 1 and tubes 3, there is no back pressure produced in the exhaust manifold of the engine, which is a decided practical advantage. As the muffler may be produced as a unit by casting, it may be 75 made and sold at a sufficiently low cost to justify its extensive use.

As will be appreciated, and as indicated herein, slight changes may be made in the construction and arrangement of the details of the invention without departing from the field and scope of the same, and I intend to include all such variations as fall within the scope of the appended claims, in this application in which a preferred form 85 only of my invention is disclosed.

What I claim is:

1. In a muffler, a central exhaust receiving tube, and lateral discharge tubes of substantially elongated U-shape communicating at 90 their inner ends with said exhaust receiving tube, the arms of each of said discharge tubes being parallel with each other.

2. In a muffler, a central exhaust receiving tube, lateral discharge tubes of substantially 95 elongated U-shaped communicating at their inner ends with said central tube at the outer end thereof, and means for dividing the column of exhaust gases as it leaves the central tube so as to direct equal parts of the gases 100 into the respective exhaust tubes, the arms of each of said discharge tubes being parallel with each other.

3. In a muffler, a central exhaust receiving tube, lateral discharge tubes of substantially 105 elongated U-shape communicating at their inner ends with said central tube at the outer end thereof, and a member projecting in-

- wardly of the discharge tubes centrally of the outer end of said central tube, said member being disposed at right angles to the plane of the lateral discharge tubes and acting to divide the column of exhaust gases so as to direct equal portions thereof into the respective discharge tubes, the arms of each of said discharge tubes being parallel with each other.
- 10 4. In a muffler, a central exhaust receiving tube, lateral discharge tubes of substantially elongated U-shape communicating at their inner ends with said central tube at the outer end thereof, a member projecting inwardly 15 of the discharge tubes centrally of the outer end of said central tube, said member being disposed at right angles to the plane of the lateral discharge tubes and acting to divide the column of exhaust gases so as to direct 20 equal portions thereof into the respective
- discharge tubes, and baffles mounted in the tubes, the outermost baffle in the central tube being disposed at right angles to said member.
5. In a muffler, a central exhaust receiving tube, and lateral discharge tubes of substantially elongated U-shape communicating at their inner ends with said exhaust receiving tube, the arms of the respective discharge tubes being disposed in substantial parallelism with the receiving tube.
6. In a muffler, a central exhaust receiving tube, and lateral discharge tubes of substantially elongated U-shape communicating at their inner ends with said exhaust receiving tube, the arms of the respective discharge tubes being disposed in parallelism with each other and with the receiving tube.

In testimony whereof I affix my signature.

RUDOLF LIBENSCHEK.
